PERFUME CAPSULE VENDING MACHINE

Milton C. Fitch, San Carlos, Calif., assignor of one-half to Emily R. Goldsmith, Redwood City, Calif.

Application August 16, 1957, Serial No. 47,404

Term of patent 14 years

(Cl. D52—2)

Fig. 1 is a right side elevation of a perfume capsule vending machine, showing my new design;
Fig. 2 is a left side elevation thereof;
Fig. 3 is a front elevation thereof; and
Fig. 4 is a perspective view thereof taken on a smaller scale.

I claim:
The ornamental design for a perfume capsule vending machine, as shown.
